(57) **CLAIM**

The ornamental design for a toothbrush body, as shown and described.

DESCRIPTION

FIG. 1 is a perspective view of a toothbrush body showing the design;

FIG. 2 is a front elevational view of the toothbrush body of FIG. 1;

FIG. 3 is a rear elevational view of the toothbrush body of FIG. 1;

FIG. 4 is a left elevational view of the toothbrush body of FIG. 1;

FIG. 5 is a right elevational view of the toothbrush body of FIG. 1;

FIG. 6 is a top plan view of the toothbrush body of FIG. 1; and,

FIG. 7 is a bottom plan view of the toothbrush body of FIG. 1.

Dash-dash broken lines shown in the drawings illustrate environment and form no part of the claimed design. Dash-dot-dash broken lines shown in the drawings define the boundaries of the claim and form no part thereof.

1 Claim, 4 Drawing Sheets
